Primary Examiner — Rhea Shields

(74) Attorney, Agent, or Firm — Snell & Wilmer L.L.P.

(57) **CLAIM**

The ornamental design for a rear light for vehicle, as shown and described.

DESCRIPTION

1.-2. Rear light for vehicles

1.1 : Perspective

1.2 : Front

1.3 : Right

1.4 : Top

1.5 : Back

1.6 : Left

1.7 : Bottom

2.1 : Perspective

2.2 : Front

2.3 : Right

2.4 : Top

2.5 : Back

2.6 : Left

2.7 : Bottom

In Embodiment 2, the spaced shade lines are for the purpose of illustrating illumination specific to the inner and outer portions of the rear light, and form no part of the claimed design.

1 Claim, 14 Drawing Sheets(56)
